WRIST-WATCH STRAP, BAND, OR BRACELET

Charles Feid, North Attleboro, Mass., assignor to
Harold E. Sweet, doing business as R. F. Sim-
mons Company, Attleboro, Mass.

Application December 29, 1933, Serial No. 704,382

16 Claims. (Cl. 224—4)

This invention relates to wrist-watch straps, bands and bracelets and particularly to a talon-type bracelet comprising opposite arcuately-shaped arms hingedly connected to the sides of the watch and resiliently operated to clasp around the wrist of the wearer.

One object of the invention is to provide an improved means for hinging the arcuate arms or talons of the bracelet to the sides of the watch-case with the hinges embodying resilient means for swinging the arms into closed relationship.

Another object of the invention is to provide hinging means of the type indicated which may be used with different types of wrist-watches having wire bails, lugs with spring-pins or other means on the watch-case for attaching the bracelet thereto.

Another object of the invention is to provide a hinge-device of the type indicated which is compact in size, neat and finished in appearance, and efficient for the purpose specified.

Another object of the invention is to provide a hinge-device of the type indicated having its mechanical elements entirely enclosed and concealed from view.

Another object of the invention is to provide a hinge-device of the type indicated which is simple in construction, convenient for application to the watch-case, and proof against derangement or getting out of order.

Further objects of the invention are set forth in the following specification which describes the device as embodied in different forms of construction illustrated by the accompanying drawing. In the drawing:

Fig. 1 is a perspective view showing a lady's wrist-watch of conventional type with spring-arms or talons connected to its sides by the present improved hinge-device;

Fig. 2 is an edge view of the watch and talon bracelet illustrating the manner in which the arms or talons may be swung into open position in placing the bracelet on and removing it from the wrist;

Fig. 3 is an enlarged partial plan view of the watch and a portion of one of the talons or arms shown as connected thereto by the present improved hinge-device;

Fig. 4 is an enlarged part-sectional detailed view of the improved hinge-device taken on line 4—4 of Fig. 3;

Fig. 5 is a similar view showing the arm or talon swung back on its hinge and also indicating its closed position;

Fig. 6 is a part-sectional view of the hinge-joint taken on line 6—6 of Fig. 5;

Fig. 7 is a composite perspective view showing a portion of the watch-case and the several parts of the hinge-joint in disconnected relationship;

Fig. 8 is an edge view of a portion of a watch-case showing the present improved hinge-joint as embodied in a bearing-member formed integral with the watch-case; and

Fig. 9 is a part-sectional view of the same taken on line 9—9 of Fig. 8.

Various types of straps, bands, linkages and bracelets are used with wrist-watches and most of these require some form of clasp or buckle for connecting their ends and adjusting them in length to fit the wrist. The present invention contemplates the use of a two-part strap, band or bracelet having opposite arcuately-shaped arms or talons hinged to the sides of the watch-case to adapt them to clasp around the wrist, thereby eliminating the use of buckles, mechanical clasps, extension-devices or the like which are apt to get out of order and become worn and broken in use. Moreover, the present talon type of bracelet provides greater ease and convenience in placing the watch on or removing it from the wrist while being adapted to fit wrists of varying size without requiring manual adjustment.

The present improved hinge-device is similar in some respects to that disclosed in an application for patent Serial No. 697,410, filed November 10, 1933, by the present inventor and Charles A. Mealy. In the device of the prior application the hinge-joint for the talon bracelet is intended for use particularly with watches having lugs on their sides to which the bracelet is connected by means of a telescopic spring-pin, pintle or the like. The present hinge-joint is adapted for use with watch-cases having lugs of the aforementioned character, but is particularly designed for use with ladies' watches, the cases of which are usually provided with loops or bails on their sides for attachment of the bracelet. The present improved hinge-joint may also be applied to use with the hinge- or bearing-member constructed as an integral part of the watch-case.

Referring to the present drawing, Fig. 1 represents a lady's wrist-watch 2 of baguette shape having loop-like wire bails 3 at its sides or ends to which different types of bracelets may be attached. The bails 3 serve as the attaching means for connecting the present improved hinge-joint to the watch-case 2, the hinge being embodied in a bearing-member 5 constructed as next described. Referring particularly to Figs. 6 and 7, 55

the bearing-member 5 is constructed with a hub-like portion 6 on the side of which is a laterally-extending cylindrical sleeve 7. The sleeve 7 may be made integral with the main bearing-member 5 and to adapt it for attachment to the bail of a watch of the type illustrated in Fig. 1 the sleeve is split longitudinally at 8 for receiving the bail. The main body of the member 5 projects to one side of the tubular portion 7 to adapt it to overlie the side of the watch-case 2 and, preferably, a curved lip or ear 10 projects therefrom at one side of the tubular portion 7 for engagement with the edge of the watch-case as shown most clearly in Figs. 4 and 6.

15 In attaching the bearing-member 5 to the watch-case 2 the slotted or split sleeve 7 is sprung over the wire bail 3 and closed together by compressing it therearound. Thereafter, the end of the lip or ear 10 may be bent over, if necessary, to 20 engage snugly against the side or edge of the watch-case to serve as an abutment for preventing the hinge-member 5 from rocking or turning on the bail. Through this arrangement a neat joinder of the hinge-member with the watch-case 25 is accomplished without unsightly projections or open seams.

The hub 6 of the bearing-member 5 is preferably of less axial length than the tubular connecting sleeve 7 but of greater diameter. The 30 hub 6 is formed with a relatively large bore or cylindrical chamber 11 extending laterally thereof and secured fast within one end of the bore is a collar or bushing 12. The bushing 12 may be forced into the bore 11 or soldered or otherwise 35 secured in place therein. Extending radially of the bushing 12 is a slot 15 registering with a slot cut through the end of the hub 6 as shown most clearly in Figs. 6 and 7.

40 The slot 15 serves as a means for anchoring the end of a helical spring 16 housed within the bore 11 and arranged to act resiliently on the talon-arm 20 which is pivotally connected to the bearing-member 5 in the manner as later explained. The spring 16, shown in detail in Fig. 7, consists 45 in a helical coil of tempered wire, one end 17 of which is adapted to project into the slot 15 while its other end extends radially in an arm 18 bent at right-angles at 19.

50 The bracelet arms or talons 20 may be of any preferred form, being herein shown as constructed from sheet-metal stamped or blanked out in strips and bent or formed double in dies. Referring to Figs. 4, 6 and 7, each talon 20 comprises overlying strips 21 and 22 of tapering outline disposed in closely abutting relationship throughout the greater part of their length. Toward their wider ends the two strips 21 and 22 are spaced apart at an increasing distance to form top and bottom walls which are connected by tapering side 55 walls 23. The ends of the top and bottom walls of the arm 20 are cut away at 24 to form a bifurcated portion having an opening proportioned to the width of the hub 6 on the bearing-member 5. The opposite portions 25 at the ends of the arm 20 are 60 thus adapted to straddle and overlie the ends of the hub 6, being provided with holes 26 for receiving a pivot-pin or rivet 30 extending axially of the bore of the hub. The arm 20 is assembled on the hinge-element or bearing-member 5 in the manner as next explained.

65 The helical spring 16 is inserted within the bore or chamber 11 with its end abutting the collar or bushing 12 and the extremity 17 of the wire is then bent around to engage in the slot 15. With 70 the end 17 of the spring 16 held in the slot 15 the

spring is placed under torsion by winding it up from its arm 18. The talon arm 20 is next placed in position with its end portions 25 straddling the sides of the hub 6, the arm 18 of the spring 16 being meanwhile inserted into the hollow end of the arm 20. The pin 30 is then inserted through one of the holes 26 in the side of the arm 20 and pushed through the coils of the spring 16. The pin 30 is thus seated in the bore of the bushing 12 with its ends projecting through the holes 26 in the sides of the bearing-portion of the arm 20 and riveted thereover to secure it in place, see Fig. 6.

With the parts assembled in the manner as above explained the hinge-joint is applied to the watch by simply slipping the split sleeve 7 over the wire bail 3 and closing it therearound while adjusting the ear 10 snugly against the side of the watch-case 2. With both of the bearing-members 5 attached to the sides of the watch in this manner the curved arms or talons 20 are controlled by their springs 16 to swing them toward each other into closed relationship; it being understood that each spring 16 is held under torsion with its arm 18 pressing against the inner or bottom wall of the hollow arm 20. Usually, the springs are wound up under such torsion that they will swing the arms 20 toward each other until the edges of the inner walls 21 of the arms strike against the flat bottom surfaces of the bearing-members 5 as indicated by dash lines in Fig. 5; the engagement of these surfaces serving to limit the swinging movement of the arms. To place the bracelet on the wrist the arms 20 are swung back into the position illustrated by the dash lines in Fig. 2 and upon their release they will be closed together to snugly clasp around the wrist with their ends in somewhat overlapped relationship, depending of course upon the size of the wrist.

40 Figs. 8 and 9 illustrate a modification in the form of the invention wherein the hinge-member is formed as an integral part of the watch-case or soldered or otherwise permanently secured thereto. In this embodiment of the invention a lug or ear 35 on the side of the watch-case 34 is formed with an enlarged bore 36 for housing the spring 16. The bore 36 has a bushing 37 at its end formed with a slot for receiving the bent end 17 of the spring 16 and the talon or arm 20 is of the same hollow construction 50 with the hinge-pin 30 riveted through holes in its sides. It will be understood that this latter form of construction of the invention is intended for use with watch-cases having bracelets applied thereto at the factory where the watches 55 are made; whereas, with the first-described form of the invention, the hinge-member is adapted to be applied by the jeweler or other tradesman selling the watch and bracelet as separate articles.

60 The attachable hinge-joint or bearing-member may be made in different sizes for watches which vary considerably in their dimensions, but a single size may be adapted to fit many different sizes of watches by shortening the tubular connection or split sleeve on the bearing-member as required. The device is therefore practically universal in its application to use, being capable of attachment to watches having either bails or lugs on their sides.

65 While the device is herein illustrated and described as embodied in a preferred form of construction with one modification as shown, it is to be understood that other changes may be made in the structure and arrangement of its 70

parts within the scope of the appended claims. Therefore, without limiting myself in this respect, I claim:

1. A band or bracelet for wrist-watches comprising opposite arms shaped to conform substantially to the contour of the wrist, and hinging means for pivotally connecting an arm to the watch-case comprising a hollow bearing-member on the case, a helical spring housed in said hollow member and held under tension, and means for pivotally connecting the arm to the bearing-member with one end of the spring acting on the arm to swing it on its pivot.

2. A band or bracelet for wrist-watches comprising a pair of, opposite talons shaped substantially to the contour of the wrist, and means for hingedly connecting a talon to the watch-case comprising a hollow bearing-member mounted on the side of the case, a helical spring housed in said bearing-member with one end secured fast therewith, and a pivot-pin extending through the end of the talon and through the bearing-member axially of the spring with one end of the spring acting against the talon to swing the latter on its pivot-pin.

3. In combination with a watch-case, a pair of talon-like arms adapted to clasp around the wrist, and means for pivotally connecting an arm to the side of the watch-case comprising a bearing-member formed with a bore with a slot communicating therewith, a helical spring housed in the bore of the bearing-member with one end engaging the slot and provided with an extension at its opposite end, and a pivot-pin extending through the bore of the bearing-member to hingedly connect the arm thereto with the extension of the spring engaging against the arm to swing the latter on its pivot.

4. In combination with a watch-case, a bearing-member fixed to the side thereof and formed with a transverse bore, an arm having a hollow portion shaped to straddle the sides of the bearing-member, a pivot-pin extending through the bearing-member and arm to hingedly support the latter, and a helical spring housed in the bore of the bearing-member with one end secured from turning therein and its opposite end extending into the hollow portion of the arm to bear against the wall thereof to swing the arm on its pivot.

5. In combination with a watch-case having a loop on its side, a bearing-member having a portion surrounding the loop to secure it to the watch-case, said bearing-member having a transverse bore, a helical spring housed in the bore of the bearing-member and held under torsion with one end extending substantially radially therefrom, a hinge-pin extending through the bore in the bearing-member, and an arm having portions straddling the sides of the bearing-member and pivotally mounted on the ends of the hinge-pin in position for the end of the spring to act to swing the arm.

6. In combination with a watch-case, a bearing-member fixed to the side thereof and formed with a transverse bore, an arm having a hollow portion at its end bifurcated to straddle the sides of the bearing-member, a hinge-pin extending through the bore in the bearing-member and engaging holes in the sides of the arm to hingedly connect the latter to the watch-case, and a helical spring housed in the bore of the bearing-member with one end held from turning and its opposite end extending into the interior of the

hollow portion of the arm to bear against the side thereof to swing the arm on its pivot.

7. In combination with a watch-case having a loop on its side, a bearing-member formed with a portion shaped to engage around the loop to attach the bearing-member to the case adjacent the side thereof, said bearing-member having a hub-like portion formed with a lateral bore, an arm having a bifurcated end adapted to straddle the hub portion of the bearing-member, a pivot-pin extending through the bearing-member and the sides of said arm to hingedly connect the latter to the watch-case, and a spring acting between the bearing-member and the arm to swing the latter on the pivot-pin.

8. In combination with a watch-case having a bail on its side, a bearing-member formed with a tubular portion adapted to fit around the bail and a portion adapted to bear against the side of the watch-case to hold the bearing-member from turning with respect thereto, said bearing-member formed with a hub-like portion having a lateral bore, an arm having a bifurcated end adapted to straddle the sides of the hub on the bearing-member, means for pivoting the arm to the bearing-member, and a spring acting between the bearing-member and the arm to swing the latter on its pivot.

9. In combination with a watch-case having a bail, a bearing-member having a portion adapted to engage around the bail and provided with means abutting a portion of the watch-case to prevent turning movement of the bearing-member on the bail, an arm hinged to the bearing-member, and a spring acting between the bearing-member and the arm to swing the latter on its hinge.

10. In combination with a watch-case having a bail on its side, a bearing-member having a longitudinally split tubular portion adapted to engage around the bail to attach it fixedly to the side of the watch-case, said bearing-member being shaped to engage a portion of the watch-case to prevent it from turning on the bail, an arcuate arm hinged to the bearing-member to swing on an axis extending transversely thereof, and a spring acting between the bearing-member and the arm to swing the latter on its hinge.

11. In combination with a watch-case having a bail, a bearing-member provided with a portion adapted to engage around the bail to attach said member to the watch-case, bendable means on said bearing-member shaped to engage a portion of the watch-case to prevent turning of the bearing-member on the bail, an arm hinged to the bearing-member, and a spring having one end held in the bearing-member and its opposite end engaging the arm to swing the latter on its hinge.

12. In combination with a watch-case having a bail, a hollow bearing-member having means to clamp around the bail for attaching it fixedly to the watch-case, means for preventing the bearing-member from turning on the bail, an arcuate arm hinged to the bearing-member to adapt it to partly encircle the wrist, and a spring housed in the bearing-member with one end held thereby and its opposite end engaging the arm to swing the latter on its hinge.

13. In a device of the type indicated, the combination of an arcuately-shaped arm, and means for hingedly connecting said arm to a watch-case to adapt it to swing with respect thereto comprising a hollow bearing-member, means for attaching said bearing-member to the bail on the side of a watch-case, means for pivoting said

arm to said bearing-member, and a helical spring enclosed in said bearing-member, said spring having one end held in the bearing-member with its opposite end engaging the arm to swing the latter on its pivot.

14. In combination with a watch-case, a hinge-pin, means for mounting the pin on the side of the watch-case, an arcuately-shaped arm hinged to the pin to adapt it to partly enclose the wrist, a helical spring coiled around the pin with one end held from turning and its opposite end acting on the arm to swing the latter, and means enclosing the spring.

15. In combination with a watch-case, a hollow bearing-member on the case, an arm pivotally connected to said bearing member at one end

and shaped to partly enclose the wrist, and a spring enclosed within said bearing-member and held under tension to act on the arm to swing the latter.

16. In combination with a watch-case, a pair of talon-like arms adapted to clasp around the wrist, means for pivotally connecting the arms to the sides of the watch-case, a helical spring extending coaxially of the pivot for each arm, a hollow bearing enclosing the spring, means for connecting one end of the spring to move with the arm, and means for connecting the opposite end of the spring to the watch-case to maintain the spring under torsion, said springs tending to hold the arms in clasped relationship.

CHARLES FEID.
